(57) **CLAIM**

The ornamental design for a spray rack, as shown and described.

DESCRIPTION

FIG. 1 is a top-front perspective view of a spray rack according to the present invention;

FIG. 2 is a top view thereof;

FIG. 3 is a left side view thereof; and,

FIG. 4 is a rear view thereof.

Portions of the spray rack are shown broken away to indicate that it has no particular length beyond what is shown.

The broken lines in the drawing views represent unclaimed portions of the power distribution module, which are shown for illustration purposes only and form no part of the claimed design.

1 Claim, 2 Drawing Sheets
